CLAIM

The design for kiosk computer, as shown and described.

DESCRIPTION

FIG. 1 illustrates a perspective view of the kiosk computer. FIG. 2 illustrates a front perspective view of the kiosk computer.

FIG. 3 illustrates a right side perspective view, the left side being a mirror image.

FIG. 4 illustrates a back perspective view of the kiosk computer.

FIG. 5 illustrates a top perspective view of the kiosk computer.

FIGS. 6 and 7 illustrate enlarged views of details A and B as shown in FIG. 1, respectively, wherein the lighting feature is off; and,

FIGS. 8 and 9 illustrate enlarged views of details A and B as shown in FIG. 1, respectively, showing radiating diagonal lines depicting the lighting feature in an illuminated position of use.

The bottom of the design is flat and unornamented.

Dashed lines are environmental or indicate detail sections and form no part of the claimed design. Surface shading is used to show the presence and/or contour of surfaces and not surface ornamentation. The radiating diagonal lines ("\\ /" and "/ \\") indicate emanating luminance, not surface ornamentation.
